WELL PACKERS
Cicero C. Brown, 8490 Katy Road, Houston, Tex.
Filed June 20, 1960, Ser. No. 37,220
4 Claims. (Cl. 166—122)

This invention relates to new and useful improvements in well packers.

It is one object of the invention to provide an improved well packer of the permanent type having means for effectively setting and anchoring the packer within a well bore and for permanently maintaining said packer in its set and anchored position.

An important object is to provide an permanent-type well packer device wherein the upper and lower gripping members are molded or otherwise secured to the elastic packing or sealing element and are movable outwardly into gripping position by the deformation of said packing or sealing element; the gripping teeth or projections of the upper member being disposed in a direction to resist upward movement of the device and the gripping teeth or projections of the lower member being oppositely disposed to resist downward movement, whereby after the packer device is once set said members maintain it in permanently anchored position within the well bore.

A particular object is to provide a well packer, of the character described, wherein an expander, which effects deformation of the packing or sealing element and outward movement of the gripping members, is constructed of an elastic material so that said expander, in effect, forms a part of the packing or sealing element; the inherent elasticity or resiliency of said expander developing a force when the packer device is in set position which force is constantly applied in a direction holding said device in set position to assure permanent anchoring thereof.

An important object is to provide a well packer, of the character described, which is adapted to be moved into set position by hydraulic fluid pressure and which has a dual piston and cylinder arrangement whereby increased pressure area is exposed to the actuating pressure and increased force is thereby applied to the packing element and anchoring means to properly set the same.

Still another object is to provide a well packer, of the character described, wherein an annular deformable bridging member may be disposed adjacent the segmental gripping slips of the packer, which member is deformed to bridge the annular gap between the packer and well pipe to thereby prevent undesirable extrusion of the material of the packing element upwardly from between the gripping slips.

The construction designed to carry out the invention will be hereinafter described, together with other features thereof.

The invention will be more readily understood from a reading of the following specification and by reference to the accompanying drawings forming a part thereof, wherein an example of the invention is shown, and wherein:

FIGURE 1 is a view, partly in section and partly in elevation, of a well packer constructed in accordance with the invention and showing the same in an unset position;

FIGURE 2 is a similar view, with the packer in set position;

FIGURE 3 is a horizontal, cross-sectional view, taken on the line 3—3 of FIGURE 1;

2

FIGURE 4 is a partial, vertical sectional view illustrating a modified form of packing element;

5 FIGURE 5 is a view, similar to FIGURE 1, of another form of the well packer with the same in an unset position;

FIGURE 6 is the packer of FIGURE 5 in fully set position;

FIGURE 7 is a longitudinal sectional view illustrating the packer of FIGURES 1 and 2, employed with dual tubing strings; and,

FIGURE 8 is a similar view, illustrating the packer of FIGURES 5 and 6 employed with a dual tubing string.

In the drawings, the numeral 10 designates a tubular mandrel or support having an axial bore 11 extending entirely therethrough. As will be explained in detail, the mandrel or main support 10 has a packing element assembly A mounted on its upper portion with a hydraulically actuated setting means, generally indicated at B, carried by the support below said assembly. The device is adapted to be lowered within a well casing C by means of a well pipe or tubing T, and when disposed in desired position in the casing, the hydraulically actuated means B is operated to deform the packing element assembly A into sealing position. Anchoring means in the form of segmental gripping members or slips 13 and 13a are embedded in the upper and lower outer peripheral portions of the assembly A and when said assembly is deformed into sealing position the gripping members are moved into gripping contact with the well casing to anchor the device therein.

Referring to FIGURE 1, the lower end of the mandrel or support 10 is externally threaded and has an annular block or base 14 secured thereto; the base functions as a lower piston which co-acts with an elongate cylinder 15 which encircles the support in spaced relationship thereto. The cylinder has its lower portion surrounding the annular base piston 14 and is initially releasably attached thereto by a shear pin 16. The upper end of said cylinder is threaded to the lower portion of an annular abutment 17 which forms the lower end of the assembly A. An intermediate annular piston member 18 is secured to the mandrel and is located within the cylinder 15 to divide the interior of the cylinder into an upper cylinder area 15a and a lower cylinder area 15b (FIGURE 2); suitable seals are carried by the piston member to seal with the walls of the mandrel and cylinder. A seal ring 19 which slidably surrounds the mandrel is supported on a shoulder 50 with the upper end of the cylinder 15 and engages the underside of the abutment 17, said ring functioning to seal off the upper cylinder area 15a. A second seal 20 is secured within the bore of the cylinder and slidably surrounds the mandrel to be movable within the lower cylinder area 15b.

When the cylinder is in the position of FIGURE 1 with the shear pin 16 connecting the cylinder to the base piston 14, the intermediate piston 18 abuts the underside of the upper seal ring 19 of the cylinder 15. At this time the lower seal ring 20 of the cylinder 15 is engaging the upper surface of said base piston. For directing pressure into the cylinder area 15a, a pressure fluid inlet port 21 extends through the wall of the mandrel and establishes a communication between the bore 11 of said mandrel and the cylinder area 15a between the upper seal ring 19 and the intermediate piston 18; a similar port 22

communicates the mandrel bore with the cylinder area 15b between the base piston 14 and the lower seal ring 20. When pressure is directed into areas 15a and 15b, the movable seal rings 19 and 20, as well as the cylinder 15 are urged upwardly and when this force is sufficient to shear the pin 16, the cylinder 15 and seal rings 19 and 20 move upwardly relative to the mandrel to apply an upward force to the abutment 17.

As has been noted, the abutment 17 forms the lower element of the packing element assembly. The particular packing element assembly A illustrated in FIGURE 1 comprises a central annular expander 26 which surrounds the tubular mandrel or support 10. The upper portion of the expander is formed with an inwardly and upwardly directed inclined surface 26a while the lower portion thereof has an inwardly and downwardly inclined surface 26b. An upper sealing ring 27 surrounds the mandrel and has its major portion overlying the inclined surface 26a of the expander 26 and above this ring a second sealing ring 28 is provided. An annular abutment 29 confines the uppermost sealing ring 28 and is in turn held against upward displacement by a retaining collar 30 which is threaded onto the upper end of the mandrel or tubular support 10. With this arrangement, the upper end of the assembly A is confined against upward movement on the mandrel.

Below the expander 26 is a sealing ring 27a similar to the ring 27 except that it is upwardly directed to overlie the major portion of the inclined surface 26b of said expander. A lowermost sealing ring 28a is located below the sealing ring 27a. The lower end of sealing ring 28a abuts and, if desired, may be molded or otherwise secured to the movable annular abutment 17. It will thus be seen that the assembly A shown in FIGURES 1 and 2 is made up of the elastic expander 26 and the superposed sealing rings 27, 28, 27a and 28a. Since the upper end of the assembly is held against upward movement, upward movement of the lower abutment 17 applies an endwise compressive force to the assembly A, deforming the sealing rings and expander in the manner shown in FIGURE 2.

For anchoring the packing element assembly in the well pipe, anchoring means in the form of upper segmental slips 13 and lower segmental slips 13a are provided. The major portion of each upper slip 13 is molded or otherwise firmly attached to the uppermost sealing ring 28 and at its upper end each slip is formed with an inwardly directed lug 31 which engages within an annular groove 32 provided in the upper abutment 29. Similarly, each lower slip 13a has its major portion molded or otherwise secured to the lower sealing ring 28a and is formed with an inwardly directed lug 33 which engages an annular groove 34 in the abutment 17.

With this mounting of the segmental slips, the endwise compressive force which will deform the packing element assembly A into its sealing position will simultaneously move the upper and lower gripping slips into engagement with the pipe wall. By reason of the lugs engaging the lateral grooves 32 and 34, the slip segments are guided in a straight radial movement which results in their gripping teeth engaging the pipe wall throughout the length of each slip. The upper slips 13 have their gripping teeth directed so as to lock the upper portion of the packer against upward movement within the pipe while the gripping teeth of the lower slips 13a are directed downwardly to lock the lower end of the assembly against downward movement within the pipe.

The mandrel 10 and its associated parts are adapted to be lowered into position by means of the well tubing T, and connection with the device is made through a coupling 35 and shear pin 36, said shear pin connecting with the upper retaining collar 30 of the assembly. An inner tubular conductor 37 has its upper end connected to coupling 35 and extends axially entirely through the device. A

flapper valve 38 may be pivotally connected to the lower end of the annular base 14 and the tubular conductor 37 has sufficient length to extend downwardly past the flapper valve to maintain the same in open position. An upper seal 39 is disposed between the tubular conductor 36 and the bore 11 of the mandrel 10, while a lower seal 39a seals off between said conductor 36 and the annular base 14. The area between the upper and lower seals 38 and 39, as shown in FIGURE 1, provides an annular space 40 which is in communication with the pressure inlet ports 21 and 22 which direct pressure to the upper and lower cylinder areas 15a and 15b. For conducting pressure from the tubing string T and the inner conductor 37 to the annular space 40, said inner conductor is formed with a radial port 41 which is located between the annular seals 39 and 39a. From the port 41, pressure from the tubing string may pass downwardly into the annular passage 40 and then to the inlet ports 21 and 22, whereby pressure may be applied to the under side of the upper and lower seal rings 19 and 20 and thereby apply an upward force to the cylinder 15.

In the operation of the well packer, the device is assembled as shown in FIGURE 1, and is connected to the well tubing string through the shear pin 36. At such time the inner tubular conductor 37 extends entirely through the mandrel or support 10 and projects outwardly from the lower end thereof to hold the flapper valve 38 in open position. When the packer has been lowered to the point at which it is to be set within the well casing C, a closure which is shown in the form of a ball 42 is dropped downwardly through the tubing and inner conductor 37 to engage a seat 43 at the lower end thereof to close the bore of said conductor. Thereafter, the pressure within the tubing string may be built up and this pressure is directed through the port 41 in the wall of the inner conductor 37, passes downwardly through the annular passage 40 into the inlet ports 21 and 22. Upon flowing through ports 21 and 22, pressure is introduced into the cylinder areas 15a and 15b and is applied to the under side of the upper and lower seal rings 19 and 20, respectively. As explained, the upper ring 19 engages the abutment 17 of the packing element assembly A, while the lower ring 20 is secured to the cylinder 15 and this application of pressure results in an upward force being applied to the cylinder 15 sufficient to shear the pin 16 and effect an upward movement of the cylinder with respect to the mandrel 10.

The upper end of the sealing assembly A is confined against upward movement by the upper retaining collar 30, and as the cylinder 15 is moved upwardly by pressure, an endwise force is applied to the packing element assembly. Such upward force moves the various parts of the assembly A to the position shown in FIGURE 2, in which position the elastic members of said assembly have been deformed and the sealing rings 27, 27a, 28, 28a and the elastic expander 26 are in packing position, being retained in such position by the engagement of the slips with the casing wall; additionally, the inherent elasticity of the expander 26, which is attempting to return to its normal undistorted position, applies a constant force through the inclined co-acting surfaces of the various seal rings of the assembly to seal rings and slips to assist in holding the unit in anchored position.

To further assist in preventing the lower portion of the assembly from moving downwardly on the mandrel, additional internal locking slips 44 may be provided. These slips are disposed within the inclined bore of the lower abutment 17 and have their teeth in engagement with the exterior surface of the mandrel 10. It will be evident that when the abutment 17 and slips 44 move upwardly on the mandrel, any tendency of the ring to move downwardly will be prevented because the slips 44 will be moved into tighter engagement with the exterior of the mandrel.

After the packer has been set, it remains permanently

anchored in the well casing. When it is desired to remove the tubing T, it is only necessary to shear the pin 36 and to lift the same upwardly to the surface. At any time that the tubing and the inner conductor 37 attached thereto is removed, the flapper valve 38 at the lower end of the device will swing to a closed position, and the device becomes a full plug within the well bore.

It is pointed out that during the setting operation the combined total area of both of the stationary pistons 14 and 18 and the combined area of movable rings 19 and 20 are available for the application of pressure. By locating the intermediate piston 18 within the cylinder 15, two separate cylinders are, in effect, provided and thus the area available for force application by the pressure is doubled. The rings 19 and 20 actually work in tandem and this provides for the exertion of a very substantial force which will assure that the packing element A and its anchoring means 13 and 13a are moved into a firm set position.

Although the packer assembly A consisting of a plurality of co-acting elements has been found satisfactory, other types of packing elements could be employed. In FIGURE 4, a solid sleeve-like packing element 45 is illustrated as mounted on the mandrel 10. Upper and lower gripping slips 13 and 13a are embedded in the ends of the packing sleeve and when an endwise force is applied to the sleeve, said sleeve is deformed into a sealing position and the slips are moved into anchoring engagement with the casing. As in the first form, the inherent resiliency of the packing sleeve 45 which is tending to return the sleeve to its initial undistorted position, is utilized to apply a continuing force to the gripping slips to thereby assure that the device will remain in its anchored position.

Although the double piston and cylinder arrangement of FIGURES 1 and 2 has been found satisfactory, it is not absolutely essential, and in FIGURES 5 and 6 a modification of the invention is shown. Referring to FIGURE 5, the packer includes a central tubular mandrel or support 110 having an annular base 114 secured to its lower end. A cylinder 115 has its lower portion surrounding the base 114 and extends upwardly therefrom. As in the first form the base functions as a stationary piston. An annular seal ring 119 supported within the upper portion of the cylinder 115 is slidable on the mandrel 110 and engages an annular abutment 117 which has threaded connection with the upper end of the cylinder. For conducting pressure into the cylinder area between the seal ring 119 and stationary piston 114, an inlet port 122 is provided in the mandrel and is in communication with an annular passage 140 formed between the mandrel 110 and an inner conduit 137. The conduit 137 has a communicating port 141 therein and seals 139 and 139a seal off between the mandrel and conduit at points above and below said port.

It will be evident that when pressure is conducted downwardly through the inner conduit or conductor 137, such pressure may pass through port 141, annular space 140, and into inlet port 122 to act against the under side of the seal ring 119. Application of force against the seal ring 119 is transmitted to the abutment 117 and cylinder 115 to shear the pin 116 and effect upward movement of the cylinder and abutment. As has been explained, this action applies an endwise compressive force to a packing element assembly A' which is mounted on the upper portion of the mandrel above the piston and cylinder assembly.

The particular packing assembly A' shown in FIGURES 5 and 6 is of slightly different construction than the packing assembly element A of FIGURE 1. Referring to FIGURE 5, the assembly A' includes a central expander 126 which is constructed of an elastic packing material and which has an inclined surface 126a at its upper end and a similar oppositely inclined surface 126b at its lower end. A lower sealing ring 128a engages the

lower portion of expander 126 and has a lower gripping slip 113a embedded or molded in its outer surface. A deformable anti-extrusion ring 50 which may be constructed of lead or other readily deformable metal surrounds the mandrel immediately below the gripping slip 113a. This ring rests upon the upper end of the annular abutment 117.

Above the expander 126 of the assembly A', an upper seal ring 128 having an upper gripping slip 113 embedded therein is provided. A deformable anti-extrusion ring 51, similar in construction to the ring 50, overlies the upper gripping slip and a retaining collar 133, which is threaded onto the upper end of the mandrel, retains the upper end of the assembly in place.

When the packer of FIGURE 5 is properly positioned within the well casing C, a closure or ball 42 is dropped downwardly to seat on an annular seat 143 at the lower end of the inner conductor 137 and thereafter pressure is applied through the tubing string T. This pressure passes

through port 141, annular space 140 and pressure inlet port 122 to act against the lower end of the seal ring 119. Upon sufficient force being applied, the pin 116 is sheared and the cylinder 115 and abutment 117 move upwardly to apply an endwise force to the lower end of the packing element assembly A'. The upper end of the assembly is held against movement by the retaining collar 133 and upward movement of the cylinder and abutment 117 results in a deformation of the assembly A' to the position shown in FIGURE 6. In such position, the expander 126,

the seal rings 128 and 128a and the deformable metal rings 50 and 51 are distorted as shown. The anti-extrusion rings 50 and 51 move outwardly into contact with the inner bore of the well casing and at the same time the gripping slips 113 and 113a are set into anchored position.

Distortion of the sealing rings and the expander effectively form a seal with the wall of the casing. As in the first form of the invention, the inherent elasticity of the expander 126 exerts a constant force which maintains the gripping slips in their engaged or anchored position. The deformation of the metallic rings 50 and 51 will prevent any flow of elastic material from between the slip segments and outwardly into the annular space between the packing device and the casing wall. If desired, the assembly may be additionally locked in its deformed or set position by gripping slips 144 which are confined within the sleeve 117; these slips function in the manner described with respect to the slips 44 in FIGURE 1, and engage the wall of the mandrel to prevent the lower portion of the assembly A' from moving downwardly.

In both forms of the invention, the packing element assembly is deformed into sealing position, and is thereafter maintained in such position as a permanent packer. The sealing elements of the assembly including the expander are all constructed of an elastic material. Therefore, when and if it becomes necessary to drill out the packer, such drilling out operation is relatively easy because it is only necessary to drill off the metallic upper slip segments. No other hard metal need be cut away in order to permit removal of the packer from the casing.

In FIGURES 1, 2, 5 and 6 the well packer assembly has been shown as run on a single string of tubing. It has been found, however, that the particular packers of FIGURES 1 and 5 are applicable for dual production and in FIGURE 7 the packer of FIGURE 1 is shown in connection with a dual tubing string. In this case, the bore 10 through the mandrel is somewhat enlarged and an elongate housing 60 having longitudinal passages 61 and 62 extending therethrough is disposed within the bore. This housing is connected to the annular base 14 by a shear pin 63. A first tubing string T1 has connection with the passage 60 and the lower end of this tubing string (not shown) passes downwardly, usually through a second packer, to communicate with a lower production zone. The second passage 62 has a second tubing string T2 connected therewith and the lower end of this passage and string is in com-

75

munication with an upper producing zone. The operation of the packer would be exactly as heretofore described with pressure being applied to the inlet ports 21 and 22 through an inlet port 64 which extends from the passage 62. Thus, by dropping a ball or closure 42, shown in dotted lines in FIGURE 7, onto a seat at the lower end of passage 62, the tubing string T2 may be pressured up to apply pressure against the seal rings 19 and 20 and thereby effect a setting of the packer.

In FIGURE 8 the form of packer shown in FIGURE 5 is illustrated in use with a dual tubing string. In this case the housing 60 having passages 61 and 62 extends through the bore 110 of the packer and is connected to the annular base 114 by the shear pin 63. The tubing strings T1 and T2 are connected in the manner described with respect to FIGURE 7. Here again, the passage 62 has the pressure port 64 and when the closure 42 illustrated in dotted lines in FIGURE 8 is dropped to close the tubing string T2, this string may be pressured up to apply upward force to the seal ring 118 and cylinder 115. Such application of pressure applies endwise force to the packing element assembly A' to set the same.

In all forms of the invention a permanent type packer is provided which can be effectively set to permanently anchor the device within a well casing. In the first form of the invention the dual cylinder areas 15a and 15b are provided to increase the available area against which pressure force may be applied. The segmental gripping slips 13 and 13a are mounted for movement only in a lateral or radial direction so that the gripping teeth thereof contact the wall of the casing throughout the length of each slip. The application of endwise force to the assembly results in a simultaneous deformation of the elastic elements of the assembly and of the radial movement of the slips into gripping position.

After the packer is set, it is permanently anchored and retained in position with the normal elastic characteristic of the elements of the packing assembly functioning to continue to apply force to the gripping elements to hold them in their anchored position. Since the use of metallic cones for expanding the slips or for expanding the packing element are eliminated, the drilling out of the packer when it becomes necessary to remove the same from the well, is facilitated.

The foregoing disclosure and description of the invention is illustrative and explanatory thereof and various changes in the size, shape and materials, as well as in the details of the illustrated construction, may be made within the scope of the appended claims without departing from the spirit of the invention.

What I claim is:

1. A well packer for use in a well pipe including, a tubular support, a packing element assembly mounted on said support and including elastic packing means which is deformable radially outwardly into sealing engagement with the well pipe by an endwise compressive force, means on the support confining the upper end of the packing means against upward movement on the support, hydraulically-actuated means movable on the support and engageable with the lower end of the packing means whereby operation of said hydraulically-actuated means deforms the packing means into sealing position, upper segmental gripping slips embedded in the upper outer peripheral portion of the packing means, lower segmental gripping slips embedded in the lower outer peripheral portion of said packing means, means for guiding each slip segment in a direction radially of the tubular support, whereby deformation of the packing means into sealing position results in a radially outward movement of the upper and lower slip segments into anchoring engagement with the pipe wall, said elastic packing means comprising an annular expander which encircles the tubular support and which is constructed of elastic material, said expander having its exterior formed with an upwardly and inwardly inclined surface at its upper portion and a

5 downwardly and inwardly inclined surface at its lower portion, an upper annular sealing element surrounding the upper portion of the expander and co-acting with the upper inclined surface thereof, and a lower sealing element surrounding the lower portion of the expander and co-acting with the lower inclined surface thereof, the application of an endwise compressive force to the packing means effecting an outward radial deformation of the sealing elements and the central portion of the expander.

2. A well packer for use in a well pipe including, a tubular support, a packing element assembly mounted on the support and including elastic packing means, anchoring members adjacent one end portion of said elastic packing means and co-acting therewith whereby deformation of the packing means of said assembly simultaneously moves the anchoring members into gripping position with the well pipe, means on the support confining one end of the assembly against upward movement, an abutment engaging the lower end of the assembly and movable on the support whereby upward movement of said abutment on the support will apply an endwise compressive force to the assembly to deform the elastic packing means thereof radially outwardly into sealing position with the well pipe, a cylinder and piston carried by the support below the abutment, means for directing pressure fluid into the cylinder to cause relative movement of the cylinder and piston, means for transmitting the relative movement of said cylinder and piston to the abutment to move the same upwardly and thereby deform the elastic packing means of the assembly into sealing position with the well pipe, said elastic packing means comprising an annular expander of deformable material and upper and lower annular sealing elements, an expander having upper and lower inclined external surfaces which are engaged by a complementary inclined surface on the bore of each sealing element, whereby endwise compressive force effects a radial deformation of the sealing elements as well as a radial deformation of the central portion of the expander.

3. A well packer as set forth in claim 1 wherein said hydraulically-actuated means comprises a cylinder encircling the tubular support in spaced relationship thereto and having its upper end secured to and extending downwardly from the lower end of said packing means, a base piston member secured to the support and having the lower portion of the cylinder encircling the same, an intermediate annular piston secured to the support and dividing the interior of the cylinder into two cylinder areas, and annular seal rings secured within the bore of the cylinder and co-acting with the base piston member and the intermediate piston, whereby the operating fluid directed into the areas of the cylinder below said seal rings imparts movement to the cylinder to apply an endwise compressive force to the packing means to thereby deform the packing means into sealing position.

4. A well packer as set forth in claim 1 wherein said hydraulically-actuated means comprises a cylinder encircling the tubular support in spaced relationship thereto and having its upper end secured to and extending downwardly from the lower end of said packing means, a base piston member secured to the support and having the lower portion of the cylinder encircling the same, an intermediate annular piston secured to the support and dividing the interior of the cylinder into two cylinder areas, and annular seal rings secured within the bore of the cylinder and co-acting with the base piston member and the intermediate piston, whereby the operating fluid directed into the areas of the cylinder below said seal rings imparts movement to the cylinder to apply an endwise compressive force to the packing means to thereby deform the packing means into sealing position, said tubular support having an inlet port therein located immediately above the base piston member and a second port immediately above the intermediate annular piston,

whereby the operating pressure fluid may be supplied to the cylinder from the bore of said tubular support.
